UNITED STATES PATENT OFFICE.

HENRY M. TAYLOR, OF NEW YORK, N. Y.

DESIGN FOR A COAT-HANGER.

SPECIFICATION forming part of Design No. 34,187, dated March 5, 1901.

Application filed December 20, 1900. Serial No. 40,589. Term of patent 14 years.

To all whom it may concern:

Be it known that I, HENRY M. TAYLOR, a citizen of the United States, residing at New York, in the county of New York and State of New York, have invented and produced a new and original Design for a Coat-Hanger, of which the following is a specification, reference being had to the accompanying drawings, forming part thereof.

10 Figure 1 is a side view of a coat-hanger, showing my design, the shank of the hanger being represented by dotted lines. Fig. 2 is a plan view thereof, and Fig. 3 is a front view.

15 As shown in the drawings, the leading or material feature of my design consists of the form in outline of the head A, which as viewed in plan in Fig. 2 is approximately oval-

shaped and from the rear portion of which a shank B projects as a continuation of the 20 minor axis thereof. The head is curved downward at its ends C or bowed, as viewed in Fig. 3, with the outer edge D thereof lying above or in a higher plane than the inner edge E, as viewed in Fig. 1.

Having described my invention, what I claim as new, and desire to secure by Letters Patent, is—

The design for a coat-hanger as herein shown and described. 30

In testimony whereof I affix my signature in the presence of two witnesses.

HENRY M. TAYLOR.

Witnesses:

W. M. SANBORN,

JULIA PEARL.
